DESIGN FOR AN AUTOMOBILE ORNAMENT PLATE

James J. Sapione, Port Chester, N. Y.

Application June 21, 1939, Serial No. 85,614

Term of patent 7 years

To all whom it may concern:

Be it known that I, James J. Sapione, a citizen of the United States of America, residing at Port Chester, in the county of Westchester and State of New York, have invented a new, original, and ornamental Design for an Automobile Ornament Plate, of which the following is a specification, reference being had to the accompanying drawing, forming a part thereof.

mobile ornament plate, showing my new design.

The characteristic features of my automobile ornament plate design are shown in solid black lines in Fig. 1 of the drawing.

I claim:

The ornamental design for an automobile ornament plate, as shown and described.

JAMES J. SAPIONE.
